UNITED STATES PATENT OFFICE

90,756

DESIGN FOR A DRESSMAKER KIT

John S. Ewaskowitz, Sawyer, Wis.

Application January 23, 1933. Serial No. 46,941

Term of patent 3½ years

To all whom it may concern:

Be it known that I, JOHN S. EWASKOWITZ, a citizen of the United States, of Sawyer, in the county of Door and State of Wisconsin, have invented a new, original, and ornamental Design for a Dressmaker Kit, of which the following is a specification, reference being had to the accompanying drawing, forming part thereof.

I claim:

The ornamental design for a dressmaker kit, as shown.

In testimony that I claim the foregoing I have hereunto set my hand at Sawyer, in the county of Door and State of Wisconsin.

JOHN S. EWASKOWITZ.
